CLAIM

(21) Appl. No.: **29/119,289**

The ornamental design for a portion of a base for a joystick controller, as shown and described.

(22) Filed: **Feb. 29, 2000**

DESCRIPTION

(51) LOC (7) Cl. **14-02**

FIG. 1 is a perspective view of the portion of a base for a joystick controller showing my new design;

(52) U.S. Cl. **D14/413**

FIG. 2 is a first elevational view thereof;

(58) Field of Search ..... D14/400, 401, D14/412-416; D21/324, 333; 273/148 B; 463/1, 30, 36-38, 46, 47; 345/156-161, 905

FIG. 3 is a second elevational view thereof taken approximately 90 degrees from the first elevational view of FIG. 2; and,

FIG. 4 is a top plan view thereof.

(56) **References Cited**

The bottom of the base forms no part of the claimed design.

U.S. PATENT DOCUMENTS

The broken line showing of the remainder of the base in FIGS. 1-4 and the handle in FIG. 1 is for illustrative purposes only and forms no part of the claimed design.
